[57] **CLAIM**

The ornamental design for dental impression tray for small animals, as shown and described.

DESCRIPTION

FIG. 1 is a perspective view of a dental impression tray for small animals showing our new design;

FIG. 2 is a bottom plan view thereof;

FIG. 3 is a top plan view thereof;

FIG. 4 is a front elevational view thereof;

FIG. 5 is a rear elevational view thereof;

FIG. 6 is a side elevational view thereof, the opposite side being a mirror image thereof.

FIG. 2
